PNEUMATIC LOOM

Lambertus te Strake, Deurne, North
Brabant, Netherlands

Filed Mar. 11, 1963, Ser. No. 264,143

Claims priority, application Netherlands Feb. 24, 1960
10 Claims. (Cl. 139—127)

This invention relates to a device for transporting threads by means of air, and to a loom provided with such a device for blowing the weft thread into the shed.

A natural selvedge can be made with pneumatic looms by blowing the weft threads in the shape of hairpins into the shed, i.e., by blowing a first measured thread-length into the shed from one side of the shed and storing a second length, of the same length as the first, of the same thread provisionally outside the shed. When the first measured length of the weft thread has been introduced and the strike has been accomplished, the second measured length of the weft thread, which has been stored provisionally outside the shed, is blown into the shed. Preferably, this occurs at both sides of the shed, so that at the two sides of the cloth a selvedge is formed which is not thicker than the middle part of the cloth.

It is an object of this invention to provide improved loom apparatus. It is a further object of this invention to provide weft inserting apparatus whereby the manufacture of the above described selvedge is simple.

According to the invention, the objects are achieved by the use of a blowing device of the injector type, in which primary air is injected through a blowing nozzle onto a mixing tube defined by a shaft, which stores a loop of thread, and also defines conduit communicating with the mixing tube for conveying secondary air to the mixing tube.

This arrangement has the advantage that the thread coming into contact with the air jet from the blowing nozzle already is in a moving air column. Further, the thread in the moving air column in the shaft does not make a frictional contact with the shaft walls, so that it becomes possible to blow the thread into the shed with a substantially smaller quantity of air and yet with a larger velocity.

A preferred embodiment is shown herein in which the blowing nozzle is spaced from the open end of the shaft so that a part of the shaft serves as a mixing tube for the secondary air.

With the apparatus of this invention, a superatmospheric pressure of only one atmosphere suffices for blowing a weft thread over a certain distance into the shed, in contrast to the previous well-known pneumatic looms in which a superatmospheric pressure of 5 atmospheres is used, and in contrast to a blowing nozzle provided with a mixing tube in which a hole or slit is formed for secondary air and in which a superatmospheric pressure of 3 atmospheres is required.

The slit described in this construction is in the shape of a flat, longitudinally extending, narrow slit formed in the central part of the shaft communicating at each side with channels, giving a cross-sectional appearance of a bar bell. Blowing devices or nozzles are positioned in enlargements of each of the channels. This provides the advantage that no separate feeding device for the weft thread needs to be used with the weft threads for obtaining a natural selvage to be laid in the shed in the form of a hairpin. The hairpin configuration is obtained when halves of a measured length of a thread are blown successively into the shed by the two free ends.

Other objects, advantages, and features of the invention will become apparent when the following descrip-

2

tion is taken in conjunction with the accompanying drawings, in which:

FIG. 1 is a plan view of a section of the weft inserting device mounted on part of a loom;

5 FIG. 2 is similar to FIG. 1 showing that the thread which has been blown into the shed is beaten up before the next weft is inserted;

FIGS. 3 and 4 are plan views in section with a portion of the inserting nozzle cut away, the section in FIG. 3 being taken along line 3—3 of FIG. 9 and the section in FIG. 4 being taken along line 4—4 of FIG. 9;

10 FIG. 5 is a cross-sectional view taken along line 5—5 of FIG. 6 showing a portion of the nozzle;

15 FIG. 6 is a fragmentary plan view partly broken away and sectioned near the open end of the nozzle;

FIG. 7 is a side view of the nozzle taken at the open end;

20 FIG. 8 is a fragmentary perspective view of a transparent model taken from the open end of the nozzle; and

25 FIG. 9 is a view in perspective of driving mechanism for the nozzle.

Referring to the drawings, on a part 10 of a loom, a feeding roll 11 is mounted and rotates with a constant velocity for supplying a thread. The speed of rotation of the feeding roll 11 depends on the working speed of the loom, the roll 11 unwinding the thread from a package, not shown. The thread is indicated by a broken line 12 and runs, via a thread guide 13, along a thread collecting suction nozzle 14 in which a suction action prevails (suction can occur intermittently). A third clamp 15, in front of the nozzle 14, is provided for a purpose hereinafter described. The thread 12 then passes to the open end 16 of an inserting nozzle or shaft 17. The shaft 17 will be described hereinafter in detail in connection with FIGS. 5—9.

30 Two nozzles 18 and 19 are defined by the shaft 17 and in the position of the shaft 17 as shown in FIG. 1 there is a loop of thread in the shaft 17, the length of which loop corresponds to the width of the shed. The wrap threads are indicated by the numeral 20. In that part of the cycle shown in FIG. 1, the nozzle 18 comes into action and blows the loop out of the shaft 17 into the shed. Thereupon, the shaft 17 turns, as hereinafter described, to the position shown in FIG. 2 and the thread passes from the cloth 21 to the thread clamp 15. When the nozzle 18 is activated, the clamp 15 is closed and retains the thread in order to be sure that the correct length of the thread is blown into the shed. The clamp 15 is controlled mechanically, its operation being a function of the yield of the feeding roll 11. In the position shown in FIG. 2, the clamp 15 is open. Since the yield of the feeding roll 11 is constant, the correct quantity of yarn is stored provisionally in the nozzle 14. Then the shaft 35 17 exerts a suction action on the thread so that a new loop of the thread is drawn into the shaft as shown in FIG. 2. Since at a given moment the shaft 17 does not continue to blow the thread into the shed and the feeding roll 11 continues to feed the thread, the thread is 40 temporarily collected by means of the suction nozzle 14. 45 The overall operation between a collecting nozzle and an insertion nozzle is disclosed in U.S. Patent No. 3,024,814 issued March 13, 1962 to L. te Strake.

50 Then the shaft 17 returns to its position shown in FIG. 3. During the movement of the shaft 17 from its position shown in FIG. 2 to its position shown in FIG. 3, the thread is cut by a knife 22 which preferably retains the free end of the thread that runs to the clamp 15 so that later a loop can be readily drawn in and not the free extremity 55 itself (FIG. 4).

60 Finally, the nozzle 19 comes into operation, the loop being blown out of the shaft into the shed so that the 65

thread takes the shape of a hairpin between the weft threads, the curved end or bight between the legs of the hairpin forming the selvedge proper.

Hence, blowing nozzles 18 and 19 work alternately. Between each period of blowing of one of the nozzles there is a suction action in order to get a loop of the thread into the shed as follows:

Nozzle 18 blows one leg of hairpin into the shed.

Shaft 17 sucks loop for other leg of hairpin.

Nozzle 19 blows said other leg of hairpin into the shed.

Shaft 17 sucks loop for first leg of the next hairpin.

Nozzle 18 blows said first leg of said next hairpin into the shed.

Shaft 17 sucks loop for other leg of said next hairpin and so on.

The shaft 17 and its operation are shown in detail in FIGS. 5-9. Near the open end 16 of the shaft 17 air jet holes or nozzles 23, 24 and 25, 26 are provided which are situated in and communicate with the widened ends or mixing portions 27 and 28 of channels 29 and 30 communicating with the edges of a slit 31 formed in the shaft 17. Nozzle 18 is formed by mixing portion 28 and air jets 25 and 26; nozzle 19 is formed by mixing portion 27 and air jets 23 and 24. Channels 29 and 30 are continually in communication with each other by the narrow slit 6. The shaft 17 serves for drawing the loop in the weft thread 12 to be blown into the shed, the approximately parallel parts of the loop being situated in the channels 29 and 30, the part of the threads connecting the parallel parts lying in the slit 31. The shaft 17 serves for storing a measured length of the weft thread until the moment that the weft thread is blown into the shed by means of the nozzles 23, 24 or 25, 26. A more detailed description of the principle of operation of weft thread storage in a shaft is set forth in my copending application Serial No. 35 84,031 filed January 23, 1961 and now U.S. Patent No. 3,110,325 issued November 12, 1963, and the above U.S. Patent No. 3,024,814.

The enlargement 27 of the channel 29 forms a mixing tube for the primary air from the jet nozzles 23 and 24 and the secondary air supplied through the channel 40 30 and the secondary air supplied through the channel 29.

Similarly nozzles 25 and 26 are arranged near the channel 30. The enlargement 28 of the channel 30 forms a mixing tube for the primary air from the nozzles 25 and 26 and the secondary air supplied through the channel 30.

Between the mixing tubes 27 and 28 the continuation of the slit 31 allows passage of the loop of thread in and out.

Because of the action of the nozzles 23, 24 and 25, 26 a powerful air current in the channels 29 and 30 comes into existence. The thread situated in the channels 29 and 30 is suspended in this air current and does not come into contact with the walls of the channels 29 and 30, so that these walls cannot exert a braking action on the thread. The secondary air current through the channels 29 and 30 toward the mixing tubes 27 and 28 contributes in giving to the thread initial velocity, so that the air nozzles need apply air friction contact on only a small part of the thread to be blown into the shed, in order to provide the required initial velocity to this thread. The nozzles 23 and 24 or the nozzles 25 and 26 may be switched on as desired, air being supplied to the nozzles 23 and 24 through a hose 32 and to the nozzles 25 and 26 through a hose 33 and shut on and off by means of valves not shown.

When the thread is drawn into the shaft 17 by means of a suction device connected to a suction opening 34 (FIG. 9), which can be closed by a valve (not shown) in a hose 35 communicating with the opening 34, the nozzles 23 and 24 or 25 and 26, respectively, are not in operation. (See copending application Serial No. 84,031, now U.S. Patent No. 3,110,325, referenced hereinbefore.)

When either the nozzles 23 and 24 or the nozzles 25 and 26 are put into operation the valve in the hose 35 is closed, so that air flow through the opening 34 is stopped.

At the same moment the interior of the shaft 17 is con-

nected to the atmosphere via an opening 36 by a vent valve (not shown) in a hose 37 coming into operation, in order to prevent the formation of troublesome pressure waves. (See copending application Serial No. 84,031, now U.S. Patent No. 3,110,325, referenced above.) Through this opening 36 secondary air can enter the channels 29 and 30.

To facilitate this entry of secondary air for the mixing tubes auxiliary channels 38 and 39 are provided in the narrow part 31 of the shaft 17 between the vent opening and the channels 29 and 30.

Instead of secondary air being drawn in through the opening 36 an additional air valve may be supplied anywhere between the closed end of the shaft and the mixing tubes. Advantageously this additional air valve is closer to the closed end to provide the longest air thread suspension currents in channels 29 and 30.

As appears from FIG. 9, the shaft may be made bent, the air nozzles and the mixing tubes being positioned in the upper part 40. The lower part may be provided with a transparent wall 41 in order to monitor the course of the thread in the shaft and to monitor whether or not the slits and channels are about to be clogged or to observe any other operation desired.

A driving mechanism for the shaft 17 is shown in FIG. 9. The shaft 17 is provided with a pin 42 in a bearing 43 of a support 44 which is any suitable part of the loom. A lever 45 is connected to the pin 42 and a rod 46 is connected between the lever 45 and a bell crank 47 pivotally mounted on a shaft 48. A roller 49 is carried by an arm of the bell crank and abuts on a cam (not shown) or other control-device which acts periodically as a function of the stroke of the loom.

There has thus been described a weft inserting apparatus for a weaving loom which comprises a shaft having formed therein a longitudinally extending thread-receiving slit opening to the atmosphere at one end of said shaft. The shaft also has formed therein a suction aperture adapted to be utilized to lower the pressure within the slit whereby a thread disposed adjacent the slit opening is drawn in a loop into the slit. Channels are also formed in the shaft which are larger than the slit and which are adjacent to and communicate with the slit. The channels also communicate with the suction aperture so that suction pull established through the suction aperture is stronger in the channels thereby maintaining the thread in a U-shaped loop when it is drawn into the slit.

The shaft is provided with air nozzle means, shown in the specification as an air nozzle formed within the shaft which communicates at one end with one of said channels, the other end adapted to be utilized to direct a jet of air through the nozzle and into the channel to transport a thread disposed in the channel out into a shed. It is to be understood that any air nozzle means which may be adapted to the use shown in here may be used to complete applicant's invention.

The shaft may also have a vent aperture formed therein providing communication between the atmosphere and the slit intermediate the suction aperture and the slit opening. One or more auxiliary channels may be formed in the shaft communicating with the vent aperture, the slit, and/or one of the channels receiving the jet of air, in order to facilitate the flow of secondary air into the channels. Venting means may be provided to admit air directly to the one of the channels as so desired.

In a preferred embodiment of the invention the shaft has formed therein an enlargement of at least one of the channels into a mixing tube for a portion of its length back from the open end. The mixing tube will cooperate with the air nozzle means as discussed hereinbefore to transport the thread on an air current into the shed. The mixing tube arrangement may be described as a separate part (as may also be done with the air nozzle, for example), the separate part being disposed to form a con-

tinuation of and to communicate with said one channel having the air nozzle therein or communicating therewith. The tube also communicates with the slit so that the thread may be drawn in and jetted forth into the shed.

In conclusion, it is pointed out that while the illustrated examples herein constitute practical embodiments of the invention, I do not limit myself to the exact details shown, since modification of the same may be made without departing from the spirit and scope of this invention.

This application is a continuation-in-part of application Serial No. 90,820 filed February 21, 1961, in the name of Lambertus te Strake and now abandoned and of application Serial No. 105,399 filed April 25, 1961, in the name of Lambertus te Strake and now abandoned.

Having described the invention, I claim:

1. Apparatus to be utilized in a loom, comprising: thread feeding means; a thread collecting means; thread clamping means; a shaft having formed therein a longitudinally extending thread receiving slit, said shaft also having formed therein a suction aperture adapted to be utilized to lower the pressure within said slit whereby a thread disposed adjacent said slit is drawn in a first loop into said slit; said slit having enlarged first and second channels formed lengthwise adjacent to and communicating with said slit, said channels also communicating with said suction aperture whereby suction pull established through said suction aperture is stronger in said channels thereby maintaining said thread in a U-shaped loop; first and second nozzles disposed adjacent the openings of said first and second channels, respectively, of said shaft; said first nozzle being adapted to blow an end of said first loop of thread disposed in said slit into a shed thereby pulling the length of said first loop in said slit into said shed; the other end of said thread being restrained by said thread clamping means; means operative after said first nozzle has ceased operation to release said thread clamp whereby the suction pull in said slit is operative to draw a second loop of thread into said slit from said thread collecting means; means operative in response to said second loop of thread being pulled into said slit for severing and clamping said thread between said shaft and said thread feeding means; said second nozzle being adapted to blow said severed end of said thread into a shed thereby pulling the length of said second loop into said shed.

2. Weft inserting apparatus for a loom comprising a shaft having formed therein a longitudinally extending thread-receiving slit opening to the atmosphere at one end of said shaft; said shaft also having formed therein a suction aperture adapted to be utilized to lower the pressure within said slit whereby a thread disposed adjacent the slit opening is drawn in a loop into said slit; said shaft having channels larger than said slit formed lengthwise adjacent to and communicating with said slit; said channels also communicating with said suction aperture whereby suction pull established through said suction aperture is stronger in said channels thereby maintaining said thread in a U-shaped loop; said shaft having an air nozzle formed therein communicating at one end with one of said channels, the other end adapted to be utilized to direct a jet of air through said nozzle and into said channel to transport a thread disposed in said channel out into a shed.

3. Weft inserting apparatus for a loom comprising a shaft having formed therein a longitudinally extending thread-receiving slit opening to the atmosphere at one end of said shaft; said shaft also having formed therein a suction aperture adapted to be utilized to lower the pressure within said slit whereby a thread disposed adjacent the slit opening is drawn in a loop into said slit; said shaft having channels larger than said slit formed lengthwise adjacent to and communicating with said slit; said channels also communicating with said suction aperture

ture whereby suction pull established through said suction aperture is stronger in said channels thereby maintaining said thread in a U-shaped loop; said shaft having an air nozzle formed therein communicating at one end with one of said channels, the other end adapted to be utilized to direct a jet of air through said nozzle and into said channel to transport a thread disposed in said channel out into a shed; said shaft having a vent aperture formed therein providing communication between the atmosphere and said slit intermediate said suction aperture and said slit opening.

4. Weft inserting apparatus for a loom comprising a shaft having formed therein a longitudinally extending thread-receiving slit opening to the atmosphere at one end of said shaft; said shaft also having formed therein a suction aperture adapted to be utilized to lower the pressure within said slit whereby a thread disposed adjacent the slit opening is drawn in a loop into said slit; said shaft having channels larger than said slit formed lengthwise adjacent to and communicating with said slit; said channels also communicating with said suction aperture whereby suction pull established through said suction aperture is stronger in said channels thereby maintaining said thread in a U-shaped loop; said shaft having an air nozzle formed therein communicating at one end with one of said channels, the other end adapted to be utilized to direct a jet of air through said nozzle and into said channel to transport a thread disposed in said channel out into a shed; said shaft having a vent aperture formed therein providing communication between the atmosphere and said slit intermediate said suction aperture and said slit opening; said shaft also having formed therein an auxiliary channel communicating with said vent aperture, said slit and said one of said channels receiving said jet of air to facilitate flow of secondary air into said one of said channels.

5. Weft inserting apparatus for a loom comprising a shaft having formed therein a longitudinally extending thread-receiving slit opening to the atmosphere at one end of said shaft; said shaft also having formed therein a suction aperture adapted to be utilized to lower the pressure within said slit whereby a thread disposed adjacent the slit opening is drawn in a loop into said slit; said shaft having channels larger than said slit formed lengthwise adjacent to and communicating with said slit; said channels also communicating with said suction aperture whereby suction pull established through said suction aperture is stronger in said channels thereby maintaining said thread in a U-shaped loop; said shaft having an air nozzle formed therein communicating at one end with one of said channels, the other end adapted to be utilized to direct a jet of air through said nozzle and into said channel to transport a thread disposed in said channel out into a shed; said shaft having a vent aperture formed therein providing communication between the atmosphere and said one of said channels to facilitate flow of secondary air into said one channel during operation of said air nozzle.

6. Weft inserting apparatus for a loom comprising a shaft having formed therein a longitudinally extending thread-receiving slit opening to the atmosphere at one end of said shaft; said shaft also having formed therein a suction aperture adapted to be utilized to lower the pressure within said slit whereby a thread disposed adjacent the slit is drawn in a loop into said slit; said shaft having channels larger than said slit formed lengthwise adjacent to and communicating with said slit; said channels also communicating with said suction aperture whereby suction pull established through said suction aperture is stronger in said channels thereby maintaining said thread in a U-shaped loop; at least one of said channels being enlarged for a portion of its length back from said open shaft end to form a mixing tube; said shaft having an air nozzle communicating at one end with said enlarged channel portion, the other end adapted to be utilized to

direct a jet of air through said nozzle and into said enlarged channel portion; said shaft having a vent aperture formed therein providing communication between the atmosphere and said slit intermediate said suction aperture and said mixing tube.

7. Weft inserting apparatus for a loom comprising a shaft having formed therein a longitudinally extending thread-receiving slit opening to the atmosphere at one end of said shaft; said shaft also having formed therein a suction aperture adapted to be utilized to lower the pressure within said slit whereby a thread disposed adjacent said slit is drawn in a loop into said slit; said shaft having channels larger than said slit formed lengthwise adjacent to and communicating with said slit; said channels also communicating with said suction aperture whereby suction pull established through said suction aperture is stronger in said channels thereby maintaining said thread in a U-shaped loop; at least one of said channels being enlarged for a portion of its length back from said open shaft end to form a mixing tube; said shaft having an air nozzle communicating at one end with said enlarged channel portion, the other end adapted to be utilized to direct a jet of air through said nozzle and into said enlarged channel portion; said shaft having a vent aperture formed therein providing communication between the atmosphere and said slit intermediate said suction aperture and said mixing tube; said shaft also having formed at least one auxiliary channel communicating with said vent aperture, said slit, and said one of said first-mentioned channels having said mixing tube formed at the end thereof to facilitate flow of secondary air into said one of said channels.

8. Weft inserting apparatus for a loom comprising a shaft having formed therein a longitudinally extending thread-receiving slit opening to the atmosphere at one end of said shaft; said shaft also having formed therein a suction aperture adapted to be utilized to lower the pressure within said slit whereby a thread disposed adjacent the slit opening is drawn in a loop into said slit; said shaft having channels larger than said slit formed lengthwise adjacent to and communicating with said slit; said channels also communicating with said suction aperture whereby suction pull established through said suction aperture is stronger in said channels thereby maintaining said thread in a U-shaped loop; and air nozzle means communicating with one of said channels adapted to direct

8
a jet of air through said channel to transport a thread out of said channel into a shed.

9. Weft inserting apparatus for a loom comprising a shaft having formed therein a longitudinally extending thread-receiving slit opening to the atmosphere at one end of said shaft; said shaft also having formed therein a suction aperture adapted to be utilized to lower the pressure within said slit whereby a thread disposed adjacent the slit opening is drawn in a loop into said slit; said shaft having channels larger than said slit formed lengthwise adjacent to and communicating with said slit; said channels also communicating with said suction aperture whereby suction pull established through said suction aperture is stronger in said channels thereby maintaining said thread in a U-shaped loop; air nozzle means communicating with one of said channels adapted to direct a jet of air through said channel to transport a thread out of said channel into a shed; and venting means for admitting air from the atmosphere to said one of said channels having said air nozzle means communicating therewith.

10. Weft inserting apparatus for a loom comprising a shaft having formed therein a longitudinally extending thread-receiving slit opening to the atmosphere at one end of said shaft; said shaft also having formed therein a suction aperture adapted to be utilized to lower the pressure within said slit whereby a thread disposed adjacent the slit opening is drawn in a loop into said slit; said shaft having channels larger than said slit formed lengthwise adjacent to and communicating with said slit; said channels also communicating with said suction aperture whereby suction pull established through said suction aperture is stronger in said channels thereby maintaining said thread in a U-shaped loop; a mixing tube larger in cross-section than one of said channels disposed to form a continuation of and to communicate with said one channel; said tube also communicating with said slit; and air nozzle means communicating with said mixing tube adapted to direct a jet of air through said mixing tube to transport a thread disposed in said one channel and said tube out into a shed.
